UNITED STATES PATENT OFFICE

DONALD E. WILLARD, OF DANVILLE, ILLINOIS

DESK WATCH HOLDER

Application filed November 19, 1927. Serial No. 234,438.

My invention relates to a device for supporting a watch on a desk, table or the like and has particular reference to such a holder or device which is readily adaptable for such purpose, which is pleasing in appearance, economical to manufacture and is arranged to removably support a watch in position to be easily observed.

An object of my invention is to provide a temporary desk support for a watch which is compact, readily portable, easily made and adapted to maintain a watch in substantially upright position for ready observance.

Another object of the invention is to provide a cast metal stand or easel for a watch made with prongs for engaging the stem of the watch and a member for supporting said stand in substantially upright position.

Generally speaking I carry out the preferred embodiment of my invention by providing a body or frame which is skeleton-like in appearance, which has members extending from the bottom thereof to serve as feet or supports for the body, projections or prongs to support a watch by engagement with a guard ring or stem thereof and a support at the rear to maintain said frame in proper position when in use.

The above recited and other objects of my invention will be apparent from the following description and drawings and will be particularly pointed out in the appended claims.

Fig. 1 is a front elevational view of the preferred embodiment of the invention.

Fig. 2 is an edge view of Fig. 1 taken from the left-hand side thereof.

Fig. 3 is an enlarged sectional view taken on line 3—3 of Fig. 2.

Fig. 4 is an enlarged sectional view taken on line 4—4 of Fig. 3, and

Fig. 5 is a view similar to Fig. 1 showing one of the modifications contemplated by my invention.

In the form of the invention shown in Fig. 1 the stand or easel comprises a body 10 which in this embodiment is made in the similitude of the letter D of the alphabet. A transverse member 11 passes through the body 10 and in this figure is shown as an arrow. Extending downwardly from the bottom por-

tion of the body 10 are feet 12, while extending upwardly from the top of the body 10 are members 13 provided at the upper end with outwardly formed prongs for supporting a watch by the guard-ring or stem. 55

At the back of the body 10 and preferably associated with the transverse member 11 is a pocket having a lower portion 15 and an upper portion 16, the lower portion 15 being provided with a cut-out or recess at 17 while the upper portion 16 is provided with a tongue 18 for purposes hereinafter explained.

For supporting the stand in substantially upright position such as shown in Fig. 2 of the drawings, a leg 19 is provided having a 65 T-head 20 adapted to enter the pocket formed by the members 15 and 16. When the T-head 20 of this leg 19 has been applied to the pocket, the prong 18 of the upper portion 16 is bent downwardly to retain the T-head in position 70 while the recess 17 in the lower portion 15 permits the leg 19 to be moved forwardly to lie against the rear side of the device.

I contemplate the manufacture of this device from malleable iron, although any other metallic substance may be employed for the purpose. 75

Making the supporting leg 19 with a hinged connection to the body makes it possible to pack the device in a relatively thin container 80 and to readily ship the same. This permits also the putting away of the device in a relatively small space when not in use.

When in use the device is put up on a table or stand as shown in Figs. 1 and 2 of the drawing, and the watch placed thereon with the guard-ring engaging the prong 14. It will be seen that the face of the watch may be readily observed when supported in this 85 position.

I claim:

1. In a device of the class described, including in combination, a skeletonized body of cast metal having feet at the bottom and projections at the top for engaging a watch, a grooved pocket in the back thereof, and a leg having a portion adapted to interlockingly engage said groove for maintaining said body in substantially upright position. 95

2. A two-part watch support formed of 100

metal, one part comprising the body and including a backing for the watch, supporting legs on said body, means for retaining the watch thereon, said means including outstanding prongs, and the second part comprising a leg having engagement with said first part, and tongue and groove means on one part for retaining the other part in operative engagement therewith.

10 3. A watch stand comprising a cast metal body having supporting legs and spaced projections for suspending a watch thereon, said body being arranged to support the back of the watch, and means for supporting said body in substantially upright position including a pocket in said body, a leg having a part hingedly received in said pocket, and means for hingedly interlocking said part in said pocket.

20 4. A watch stand comprising a body formed to provide a back support for the watch and having supporting legs and watch suspension elements, a transverse member on the rear of said body, a groove in said member having its under side cut away intermediate its ends, a support member having a part received in said groove and another part adapted to contact with the surface which supports the body and to fold back into said cutaway portion against said body, and means for hingedly interlocking said first supporting part in said groove.

30 5. A body formed to provide a back support for the watch and having supporting legs and watch suspension elements, a transverse member across the rear of said body, a groove in said member having its under side cut away intermediate its ends, a T-shaped support member, the T-head of which is received in said groove and its stem is adapted to contact with the surface which supports said body and to also fold back into said cutaway portion against said body, and a tongue associated with said groove for hingedly interlocking said T-head in said groove.

40 6. In a watch stand, a body formed to the shape of a letter of the alphabet, legs at the bottom of such letter body and outwardly projecting watch suspension prongs at the top thereof, a member extending across said letter body near its mid part, and a supporting leg hinged to said member at the rear of said body, said leg being limited in movement in one direction to maintain the body in upright position, and being foldable in the opposite direction against said body.

50 7. In a watch stand, a body formed to the shape of a letter of the alphabet, legs at the bottom of such letter body and outwardly projecting watch suspension prongs at the top thereof, a member extending across said letter body near its mid part, said member and letter body lying in substantially the same plane to serve as a solid backing for the watch when it is suspended from said prongs,

and a supporting leg hinged to said member for uni-directional movement whereby said body is maintained in a substantially upright position and said supporting leg may be collapsed against the rear of the letter body.
